UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed September 7, 1923. Serial No. 661,359.

To all whom it may concern:

Be it known that I, JOHN WICKS, a citizen of the United States of America, and a resident of Oak Park, Cook County, and State 5 of Illinois, have invented certain new and useful Improvements in Telephone Systems, of which the following is a specification.

The present invention relates in general to traffic intercepting equipment for use in 10 connection with automatic telephone systems, but is more particularly concerned with intercepting equipment used in a multi-office system; and the object of the invention is the provision of means for causing calls, 15 usually intercepted by operators at the office in which they originate, to be intercepted by operators located in a centralized office.

Heretofore the usual practice, so far as applicant is aware, has been to provide intercepting operators' positions at each office. 20 Where the number of calls to be intercepted in an individual office are few calls cannot be economically intercepted. By trunking these calls to a centralized office provided with intercepting operator's equipment a single operator may, during slack periods, efficiently 25 handle all of these calls for several offices, thereby effecting quite a saving in the number of operators required.

Referring to the drawings comprising 30 Figs. 1 to 11, inclusive, Figs. 1 to 5, when laid out and arranged in the manner shown in Fig. 10, illustrate sufficient circuits and apparatus of an automatic telephone system 35 to enable connections to be set up between a toll operator and a subscriber's station by way of a toll switch train, and to also enable a calling subscriber to set up connections over a local switch train.

Figs. 1 and 7, when Fig. 7 is placed with the conductors at the right thereof in alignment with the correspondingly indicated conductors in the upper portion of Fig. 1 extending from relay group RG¹, illustrate 40 the necessary circuits and apparatus required for trunking calls, extended to a dead level of the first toll selectors, to call signal equipment at a centralized operator's position.

When Figs. 1 to 5 and 8 are laid out as 45 shown in Fig. 10, Fig. 7 may be similarly used in conjunction with relay groups RG², RG³ and RG⁴ to illustrate how calls to be intercepted from dead levels in selectors E,

F and dead line contacts in connector H, 55 may be trunked to a centralized operator's position.

Fig. 6 shows an intercepting operator's 60 cord circuit suitable for answering calls trunked to the intercepting operator's position.

Figs. 4 and 8, when laid out and arranged 65 in the manner shown in Fig. 11, illustrate sufficient telephone apparatus and circuits for switching a subscriber's line from connection with a line switch into connection with conductors terminating in call signal equipment.

Fig. 8 in conjunction with Fig. 9, when 70 laid out and arranged as shown in Fig. 11, illustrates sufficient equipment for answering and extending such calls to an operator's position equipped with facilities for completing connections to automatic or manual subscriber's lines.

Referring more in detail to the drawings, 75 Fig. 1 shows a portion of a toll line X terminating in a jack J, and having associated with it the usual relay equipment required to control the call signal lamp 8 and the busy visual 7.

The left hand portion of the toll operator's 80 cord circuits, such as the cord circuit O, are the same as are usually used at toll operators' positions, while the right hand portion of these cords are modified to enable 85 the operators to control automatic switches and to get answering supervision.

The selector D is of the well known Strowger type and is wired in accordance with the usual two-wire practice. 90

The relay group RG¹ is part of the equipment used in intercepting calls extended to a dead level of the selector D.

Fig. 2 shows a toll transmission selector 95 E with its associated relay equipment B. This selector is mechanically the same as the selector D.

The relay group RG² is part of the equipment used for intercepting calls extended to a dead level in the selector E. 100

Fig. 3 shows a connector H, which is of the usual Strowger type, but which has its circuits so arranged that it may be operated either as a toll or regular connector.

Fig. 4 shows a line switch C', which is of 105 the usual nonrestoring or rotary type. This

switch is individual to the substation A' which is of the usual type used in automatic practice.

A portion of a main distributing frame 421 is shown and has springs 422, 424, 426 and 428 for connecting the line of substation A' with its line switch C', through the medium of the usual line protecting apparatus (not shown).

10 The connecting link or cord O³ is provided at one end with appropriate springs for plugging into the springs in the main distributing frame of any desired line, and when plugged in it disconnects a line from 15 its connection with the connector banks and connects the conductors of the line and the conductors extending to the connector banks to separate conductors in the cord. This 20 cord is provided at its other end with appropriate plugs for connecting two of its conductors to conductors terminating in an answering jack at a local operator's position, while connecting the other two of its conductors to the relay group RG³. In 25 other words this connecting link O³ is for use in re-routing calls to and from subscribers' lines which are temporarily out of order.

Fig. 5 shows a calling station A, a line 30 switch C, and a selector F, which are identical to the substation A', line switch C', and selector D, respectively.

The relay group RG⁴ is part of the equipment used for intercepting calls extended to 35 a dead level in the selector F.

Fig. 7 shows a line switch C², and a master switch MS which are of the well known Keith type. There is a line switch C² individual to each of the relay groups RG¹, 40 RG², etc. As is well known, the master switch MS is common to a number of the line switches, such as C², and is provided for maintaining all such idle line switches with their plungers positioned before idle 45 trunks. These line switches have access to trunk lines extending to and terminating in jacks, such as the jack J⁵.

Fig. 6 shows an operator's cord circuit O', for use in answering calls which have been 50 trunked via line switches, such as C², from the various offices in the system to jacks, such as J⁵, located before intercepting positions in the centralized office.

55 *Calls from a distant office to subscribers' lines.*

In order to clearly describe the invention, it will be necessary to know just what operations take place when a toll connection is 60 completed by the toll operator, and for this purpose it will be assumed that a call comes in over the trunk line X and that the operator proceeds to complete the connection.

When signalling current is transmitted 65 over the trunk line X from the distant ex-

change, a ring-up relay 1 energizes and completes a locking circuit for itself at its armature 3, and at this same armature completes a circuit for the call signal lamp 8 in the usual manner. The operator upon noticing the lighted condition of lamp 8 proceeds to answer the call by inserting the plug P of her cord circuit into the jack J, causing the energization of cut-off relay 2 and sleeve relay 11, respectively. Relay 2 upon operating, at its armatures 4 and 6, breaks both the energizing and locking circuits of relay 1. This relay, accordingly, deenergizes. Relay 2 at its armature 5 also completes a circuit for the busy signal 7 70 and its multiples to notify operators at other positions that this trunk line is in use to prevent it being seized for outgoing service. Relay 11 upon operating prepares a circuit for lamp 12 and relay 14, which 75 circuit will be completed later. The operator may now throw her key K in listening position and converse with the distant operator to ascertain the number of the desired subscriber's line. Assuming now that the 80 station A' is desired, the operator proceeds, after making the usual busy test, by inserting the plug P' into an idle jack J', which is connected with conductors terminating in a toll selector D. This results in the operation of the line relay 26 over a circuit which may be traced from battery, upper winding of relay, resting contact of armature 55 and the said armature, tip side of jack J', tip contact of the plug P', through 85 springs of the key K', upper right hand winding of the repeating coil R, winding of the polarized relay 20, lower right hand winding of the said repeating coil, lower 90 springs of the key K', ring contact of the plug P', ring side of the jack J', conductor 57, armature 51 and its resting contact, and the lower winding of relay 26 to ground. The line relay energizes and completes a circuit for slow release relay 28 which also 95 energizes. Relay 28 upon operating, at its armature 29, grounds release trunk 24, causing the energization of sleeve relay 22 of the operator's cord circuit, and at its armature 31 prepares the usual operating circuit 100 for the series relay 34 and the vertical magnet 35. Relay 22 upon operating, disconnects the tertiary winding of the operator's 105 head set. The current flow through the polarized relay 20 is in the wrong direction 110 for it to operate at this time. The operator, immediately after plugging up the connection, throws her calling device key K', substituting the calling device S for the polarized relay, and operates her calling device 115 in accordance with the first digit in the telephone number of substation A'. When the calling device is operated in accordance with the first digit of the number, a series of 120 interruptions is produced in the circuit of the 125 130

line relay 26. Responsive to this series of impulses, relay 26 deenergizes momentarily and at each deenergization sends an impulse to the series relay 34 and vertical magnet 35. 5 By the operation of the vertical magnet the switch shaft is raised step by step until the wipers 41—43, inclusive, stand opposite the level of bank contacts in which are terminated the trunk lines leading to the desired 10 group of toll transmission selectors. The slow acting relay 34 is energized in series with the vertical magnet and maintains its armature continuously attracted throughout the vertical movement of the switch. As 15 soon as the switch takes one vertical step a circuit is also completed for stepping relay 36. This circuit extends from battery, winding of the said relay, interrupter springs of motor magnet 38, off normal springs 53, closed on first vertical step, working contact 20 of armature 33 and the said armature, and the grounded release trunk conductor 24. The stepping relay, upon energizing, completes a locking circuit for itself at its armature 37. At the end of the vertical 25 movement of the switch, series relay 34 deenergizes and completes a circuit for the rotary magnet 38, which extends from the grounded release trunk conductor 24, armature 33 and its resting contact, armature 39 and its working contact, and the winding of the rotary magnet 38 to battery. The rotary magnet is accordingly energized and advances the wipers 41—43, inclusive, into 30 connection with the first set of bank contacts in the selected level. Near the end of its stroke the rotary magnet breaks the circuit of the stepping relay 36, which is accordingly deenergized to open the circuit 35 of the rotary magnet. Both the stepping relay 36 and the rotary magnet 38 having deenergized, the operation now depends upon whether the test contact of the trunk with which the test wiper 42 is in engagement is busy or is not busy. If this trunk 40 is busy its test contact will have a ground potential upon it and a circuit will be established which extends from ground on the said test wiper 42, armature 40 and its resting contact, off normal springs 53, interrupter 45 springs 50, and the winding of relay 36 to battery. By current flow over the above circuit the stepping relay 36 is again energized and again closes a circuit of the 50 rotary magnet 38 which, in turn, operates to advance the switch wipers into engagement with the next set of bank contacts. This operation continues as long as the test wiper 42 continues to engage grounded test contacts. As soon as the first non-grounded 55 test contact is reached, which we will assume to be the contact 45 associated with the trunk line conductors 81—83, the stepping relay 36 will not again be energized and the rotary movement of the switch will cease.

The switching relay 54 which heretofore has been short circuited is now energized over the following circuit: grounded release trunk conductor 24, winding of relay 54, off normal springs 53, interrupter springs 50, 70 and the winding of stepping relay 36 to battery. The resistance of relay 54 is very high compared with that of relay 36, and therefore relay 36 is not energized at this time. Relay 54, however, energizes and at 75 its armature 40 connects the test wiper 42 to grounded conductor 24 in order to make the multiples of the test contact 45 busy to other switches, opens a point in the circuit of release magnet 30 at its armature 52, and 80 at armatures 51 and 55 disconnects the line relay 26 from in bridge of the trunk conductors 56 and 57 and substitutes the conductors 81 and 83 across which are bridged the windings of line relay 141 of the toll 85 transmission selector E. Line relay 141 is energized and completes a circuit for slow acting release relay 143. Upon operating, relay 143 at its armature 147 connects ground to release trunk conductor 82. It 90 will be understood that this ground is applied before the slow release relay 28 in the selector D has deenergized, and therefore this latter switch is prevented from releasing at this time. Relay 143 also at its armature 146 prepares a circuit for the series relay 150 and vertical magnet 149 in the usual manner.

The toll operator may now operate her calling device in accordance with the second digit of the desired number. By this operation a series of interruptions is produced in the circuit of line relay 141. At each deenergization, an impulse of current is sent over a circuit extending from the grounded 100 armature 144 and its resting contact, armature 146 and its working contact, armature 155 and its resting contact, windings of relay 150, and the vertical magnet 149 to battery. The operation of the vertical magnet 110 149 causes the switch wipers to be raised opposite the desired group of bank contacts. The slow acting relay 150 operates and remains energized throughout the vertical movement of the switch. Slow relay 115 150 at springs controlled by its armature 148 closes a circuit for relay 108. Relay 108 upon operating at its armature 109 completes a locking circuit for itself independent of the relay 150, at its armature 110 120 opens a point in the operating circuit of reversing relay 128, and at its armatures 106 and 107 disconnects the winding of the supervisory relay 112 from in bridge of the trunk line and substitutes the resistance element 115 to improve an operating circuit which will be traced later. As soon as the wipers of the switch are raised one step the off normal springs 134 and 135 close, completing a circuit for stepping relay 162 as 130

follows: ground, working contact of armature 145 and the said armature, working contact of armature 148 and the said armature, off normal springs 134, and the winding of relay 162 to battery. Relay 162 upon operating, at its armature 164, completes a locking circuit for itself, and at its armature 163 closes a point in the operating circuit of the rotary magnet 166. At the end 10 of the vertical movement of the switch, the slow relay 150 deenergizes and at springs controlled by armature 148 completes an initial energizing circuit for the rotary magnet 166. This circuit extends from 15 grounded working contact of armature 145 and the said armature, springs controlled by armature 148, armature 163 and its working contact, and the winding of rotary magnet 166 to battery. The rotary magnet in 20 operating moves the wipers 171—174, inclusive, into engagement with the first set of contacts in the selected level, and near the end of its stroke breaks the locking circuit of stepping relay 162 at interrupter 25 springs 161. Stepping relay 162 deenergizes and at its armature 165 closes a point in a circuit including the test wiper 173. If the trunk line associated with the first contact set is busy, the test contact engaged 30 by the wiper 173 will be grounded and a new circuit will be completed for stepping relay 162 extending from grounded wiper 173, resting contact of armature 165 and the said armature, armature 156 and its resting 35 contact, interrupter springs 161, off normal springs 134 and the winding of stepping relay 162 to battery. Stepping relay 162, upon energizing, again completes the previously described circuit for rotary magnet 40 166. This alternate operation of stepping relay 162 and the rotary magnet take place as long as the wiper 173 engages grounded or busy test contacts. As soon, however, as the wiper 173 engages an ungrounded test contact 45 the stepping relay 162 does not energize. Switching relay 152 which has previously been short circuited by the grounded test wiper 173 now operates over the following circuit: grounded working contact of armature 145 and the said armature, winding of switching relay 152, interrupter springs 161, off normal springs 134, and the winding of stepping relay 162 to battery. The resistance of relay 152 is very high 50 compared with that of relay 162, and therefore relay 162 does not energize at this time. Relay 152, however, operates and at its armature 156 connects direct ground to the wiper 173 to make this trunk busy to other 55 selectors, such as E, at its armature 154 connects the wiper 172 to the conductor 151 for a purpose which will be later made clear, and at its armatures 153 and 157 extends the trunk conductors 132 and 133 into connection with the conductors 167 and 170.

which extend to the relays 312 and 326 of the connector H. Relays 312 and 326 now operate over a circuit extending from battery, upper windings of said relays, resting contact of armature 331 and the said armature, conductor 167, bank contact 175, wiper 171, working contact of armature 153 and the said armature, working contact of armature 139 and the said armature, armature 118 and its resting contact, upper right hand winding of the repeating coil R, resistance 100, armature 107 and its working contact, resistance 115, resistance 101, lower right hand winding of the repeating coil, resting contact of armature 117 and the said armature, conductor 133, armature 157 and its working contact, wiper 174, bank contact 178, conductor 170, armature 334 and its resting contact, and the lower winding of relay 312 to ground. Relay 312 upon operating completes a circuit for relay 314 which also operates, at its armature 315 grounds the test conductor 302 terminating in bank contacts of local selectors, such as the selector F (Fig. 5), at its armature 317 applies ground to the conductor 169, and at its armature 316 prepares an operating circuit for the vertical magnet 311 and series relay 318 in the usual manner. Relay 326 upon operating, at its armature 327, prepares a point in the operating circuit of relay 332, removes one of the multiple ground connections from conductor 169, and completes a locking circuit for itself at armature 328.

The connector H is now ready to be operated under the control of the calling device S. When the dial is actuated in accordance with the next digit in the number of the subscriber at substation A', a series of interruptions is produced as before in the circuit of relay 141 of the toll transmission selector E causing armature 139 to retract a corresponding number of times to bring about a series of deenergizations of the line relay 312. At each deenergization, the line relay 312 transmits a current impulse through the series relay 318 and the vertical magnet 311 to battery. This circuit may be traced from the grounded armature 313 and its resting contact, armature 316 and its working contact, off normal springs 360 and 322, windings of the series relay 318, and the vertical magnet to battery. This is the circuit over which the first impulse is transmitted. At the first upward step of the switch shaft, however, the off normal springs are shifted and the circuit extends from the working contact of armature 316 to off normal springs 360 and 361, armature 319 and its working contact and the windings of relay 318 and vertical magnet 311 to battery. By the operation of the vertical magnet, the switch shaft is raised step by step until wipers 356—358, inclusive, stand

opposite the level of bank contacts in which the line of substation A' is terminated. The slow acting relay 318, which is energized in series with the vertical magnet, maintains its armature attracted throughout the vertical operation of the switch. When this relay energizes at the beginning of the vertical movement, it closes the following circuit for the ring cut-off relay 335 in multiple with the holding circuit of relay 326: From grounded conductor 302, armature 328 and its working contact, working contact of armature 329 and the said armature, and the lower winding of relay 335 to battery. Relay 335 upon operating, at its armature 337, completes a locking circuit for itself independent of the armatures controlled by relay 318 and 326, and at its armatures 336 and 338 disconnects generator 20 and ground from the conductors 362 and 363. At the end of the vertical movement of the switch, the slow acting relay 318 deenergizes and prepares the connector for operation to move its wipers in a rotary direction.

The toll operator may now operate the dial of her calling device S in accordance with the final digit of the called subscriber's number. The interruptions produced are repeated as before through the medium of line relay 141 and cause another series of deenergizations of the line relay 312 of the connector H. At each deenergization the line relay now sends a current impulse through the rotary magnet 364 over the following path: Grounded armature 313 and its resting contact, armature 316 and its working contact, off normal springs 360 and 361, armature 319 and its resting contact, resting contact of armature 342 and the said armature, armature 352 and its resting contact, and the winding of rotary magnet 364 to battery. In response to these impulses, the rotary magnet operates to rotate the wipers 356-358, inclusive, into engagement with the particular set of bank contacts in which the line of substation A' terminates, these bank contacts being the contacts indicated in the drawing by the reference numerals 366, 367 and 368. The slow acting relay 345 is energized in parallel with the rotary magnet and retains its armatures attracted throughout the rotary movement of the switch. At its armature 346, relay 345 connects the test wiper 357 to the winding of the busy test relay 340, and at its armature 347 closes a shunt around the armature 342 of relay 340 to guard against the possibility of the said relay being momentarily energized while the test wiper 357 is passing over busy test contacts.

Called line busy.

In order to afford an opportunity to explain the operation of the busy test cir-

cuits, it will be assumed that when the line of substation A' is called at this time it is busy. In such case, the test contact 367 will be grounded and when the test wiper 357 makes connection with the test contact a circuit will be completed for the test relay 340, this circuit being traceable as follows: grounded test contact 367, wiper 357, armature 346 and its working contact, resting contact of armature 355, and the winding of test relay 340 to battery. The test relay is energized over the above circuit, and when the slow acting relay 345 deenergizes at the end of the rotary movement of the switch the test relay becomes locked up by means of the following circuit: grounded conductor 302, armature 341 and its working contact, springs controlled by armature 346, resting contact of armature 355 and the said armature, and the winding of test relay 340 to battery. Relay 340 at its armature 342 opens a point in the operating circuit of slow relay 345 and rotary magnet 364, and at its armature 343 a lead from the busy machine Q is connected to the lower line conductor 170 by way of springs controlled by armature 334, conductor 325, condenser 305, springs controlled by the armature 308, and the resting contact of armature 334 and the said armature to conductor 170. If the operator or subscriber in the distant office is listening in on the trunk line they will hear the busy signal, which will inform them that the call cannot be immediately completed.

The toll operator at the local office having dialled the complete number, now restores the key K' to normal, again inserting the polarized relay 20 in bridge of the extended trunk line. Since the line called is busy the direction of current flow in the conductors 56 and 57 has not been changed and relay 20 therefore does not operate in the proper direction to cause the lamp 19 to glow. The operator is therefore notified of the busy condition of the called line by the lamp 19 not glowing and also by the busy tone if she still has her key K' thrown in listening position.

The operator now withdraws the plugs of the cord O from the associated jacks. The removal of the plug P' from the jack J' causes the circuit of line relay 141 of the selector E to be opened. This relay upon deenergizing, at its armature 144, breaks the circuit of release relay 143 and completes a circuit for relay 158 and the release magnet 168, which may be traced as follows: grounded armature 144 and its resting contact, armature 146 and its resting contact, off normal springs 135 and the windings of relay 158 and of the release magnet in multiple to battery. The operation of magnet 168 causes the selector E to restore to normal. Relay 158 upon operating, at its

armature 159 completes a circuit for itself and for the release magnet independent of the ground applied by the relay 141 so that the release of selector E cannot be prevented 5 by the selector being seized before it has fully restored. Relay 158, at its armature 160, introduces a high resistance in series with the lower winding of relay 141 to prevent the reoperation of relay 141 by the 10 discharging of condenser 197 when the circuit of 141 is opened, and at armature 165 disconnects the wiper 173 from the winding of switching relay 152 while the switch is restoring. Relay 143 upon retracting its 15 armatures removes ground from the release trunk conductor 82, causing the release of the switching relay 54 of the selector D. Relay 54 at its armature 52 completes a circuit for the release magnet 30, causing the 20 selector D to also restore to normal. Relay 141 at its armature 139 also opens the circuit of line relay 312 of the connector H. The line and release relays 312 and 314 therefore deenergize and complete a circuit 25 for the release magnet 330. This circuit extends from the grounded armature 313 and its resting contact, armature 316 and its resting contact, armature 309 and its resting contact, off normal springs 323, and the 30 winding of release magnet 330 to battery, causing the connector H to restore to normal.

Called line idle.

35 It will now be assumed that the line of substation A' was idle when the connector seized it. Under these conditions the test wiper 357 finds battery potential instead of ground, and the test relay 340 therefore 40 does not energize. Upon the deenergization of slow relay 345 a moment later, a circuit for switching relay 348 is completed as follows: from grounded release trunk conductor 302, armature 341 and its resting contact, upper winding of switching relay 348, resting contact of armature 346 and the said 45 armature, wiper 357, test contact 367, conductor 371, winding of cut-off relay 406 of the subscriber's line switch, and the rotary magnet 413 to battery. Due to a mechanical interlocking device on the line switch C', relay 406 only operates its armatures for a sufficient distance to disconnect the normal battery and ground connections from 50 the called line. Relay 348, however, fully operates, and at its armature 353 completes a locking circuit for itself. This locking circuit may be traced from the grounded working contact of armature 145 of relay 143 (Fig. 2), working contact of armature 156 and the said armature, armature 165 and its resting contact, wiper 173, bank contact 177, conductor 169, armature 353 and its working contact, and the lower winding of 55 switching relay 348 to battery. The relay 60

348 at armature 351 applies direct ground to the test wiper 357 to make the test contact 367 busy to other connector switches, at its armatures 352 and 355 opens points in the operating circuits of the motor magnet 364 and test relay 340, respectively, and at armatures 349 and 354 close points in the talking circuit. Relay 348 in addition to completing a locking circuit for itself at armature 353 as previously described, also completes at this same armature a circuit for relay 332. This latter relay upon operating, at its armatures 331 and 334, disconnects the regular trunk line conductors 324 and 325 and substitutes therefore the toll conductors, at its armature 333 disconnects ground from the holding circuit of ring cut-off relay 335 of the connector H and relay 108 of the relay equipment B, and at this same armature completes a new locking circuit for relay 326. Relay 108 deenergizes and at its armature 109 completes a new holding circuit for relay 335 before this relay has had time to deenergize. This circuit may be traced from armature 116 of the relay 114 and its resting contact, resting contact of armature 122 and the said armature conductor 119, resting contact of armature 109 and the said armature, conductor 151, working contact of armature 154 and the said armature, conductor 140, wiper 172, bank contact 176, conductor 168, armature 337 and its working contact, and the lower winding of ring cut-off relay 335 to battery. Relay 108, also, at its armatures 107 and 106, again connects the winding of supervisory relay 112 in bridge of the conductors 104 and 105, and at its armature 110 completes a circuit for reversing relay 128. Relay 128 upon operating, at its armatures 127 and 129, reverses the direction of current flow as regards conductors 81 and 83, for a purpose which will be subsequently made clear, and at its armature 126 connects the alternating current relay 130 in bridge of conductors 81 and 83. 105

110 This time when the operator restores key K' to normal, the current flow in the conductors 56 and 57 having been reversed by the energization of reversing relay 128, the polarized relay 20 operates in the proper direction to complete the circuit of lamp 19. The glowing of lamp 19 indicates to the operator that the called line is idle, and that she may initiate the automatic ringing at any time. In order to do this the operator momentarily throws her key K' in the proper direction to transmit a ringing current impulse out over the conductors 56 and 57, which now extend by way of conductors 81 and 83 to the alternating current relay 130 which was bridged across these latter conductors when the reversing relay 128 operated. Relay 130 now operates and, at its armature 131, completes a circuit for slow 115 120 125 130

release relay 114. Upon operating, relay 114 at its armature 116 temporarily removes ground from the previously described holding circuit of the relay 335. This latter relay deenergizes and at its armatures 336 and 338 connects interrupter generator and ground to the conductors 362 and 363 which have been extended into connection with the line of substation A', causing the signalling device thereat to be operated. When the called subscriber responds, the current flow through the upper winding of the cut-off relay 335, which was included in this circuit, is increased sufficiently to cause this relay to operate and at its armatures 336 and 338 and their working contacts complete the talking circuit, and at its armature 337 locks itself up over the previously described locking circuit, the relay 314 being again deenergized by this time. An operating circuit is now completed for the supervisory relay 112 in the relay equipment B of the toll transmission selector E. This circuit may be traced from grounded resting contact of armature 106 and the said armature, resistance 101, lower right hand winding of the repeating coil R, conductor 105, resting contact of armature 117 and the said armature, conductor 133, armature 157 and its working contact, wiper 174, bank contact 178, conductor 170, armature 334 and its working contact, working contact of armature 338 and the said armature, armature 354 and its working contact, wiper 358, bank contact 368, conductor 372, (Fig. 4), springs 428 and 426 which include the usual protective apparatus (not shown) to the signalling apparatus at station A' and back through the springs 422 and 424 of the protective apparatus, conductor 370, bank contact 366, wiper 356, working contact of armature 349 and the said armature, conductor 362, armature 336 and its working contact, working contact of armature 331 and the said armature, conductor 167, bank contact 175, wiper 171, working contact of armature 153 and the said armature, working contact of armature 139 and said armature, conductor 132, armature 118 and its resting contact, upper right hand winding of the repeating coil R, resistance 100, armature 107 and its resting contact, and the winding of the relay 112 to battery. Relay 112 upon operating, at its armature 113, completes a circuit for relay 120. This relay in turn operates and at its armatures 123 and 125 disconnects the line relay 141 from connection with the conductors 81 and 83, at its armature 123 completes a local holding circuit for maintaining relay 141 energized, and at its armature 122 switches the conductor 119 into connection with its grounded contact, which is independent of the control of slow relay 114, so that the operator cannot again unlock the ring cut-off relay, while the called subscriber has his receiver off the hook, by operating her ringing key. The removal of the line relay from bridge of conductors 81 and 83 causes the polarized relay 20 to deenergize, thereby extinguishing lamp 19 indicating to the operator that the called subscriber has responded. The operator after ascertaining that the subscriber on the line is the subscriber wanted, and assuming that the calling subscriber is waiting on the line, restores key K to normal and permits conversation to proceed.

If for any reason the operator wishes to recall the subscriber at A', either when the receiver has been replaced or when the called subscriber has merely left the telephone with the receiver off the hook, she may do so by again operating her key K' as before.

In case the subscriber replaces his receiver on the switch hook the relays 112 and 120 deenergize, and when the operator operates key K' the automatic ringing operation is initiated and cut off in the manner previously described.

If the called subscriber has left the receiver off the hook, relays 112 and 120 will be energized when the operator throws her key K'. This time when relay 114 operates it completes a local holding circuit for relay 112 at contacts controlled by armature 118 so that relays 112 and 120 remain energized. Since the ring cut-off relay 335 is locked up over the grounded working contact of armature 122 of relay 120 it will not be deenergized at this time, but instead direct generator and ground are connected to the called line by way of armatures 121 and 124 of relay 120. This generator is applied only during the time the relay 114 is operated.

At the termination of the conversation, the calling and called subscribers replace their receivers upon their respective switchhooks. The replacement of the receiver at the calling station causes the usual disconnect supervisory signal to be operated at the distant operator's position. The distant operator will thereupon pull down her cord circuit, and before disconnecting from the toll line X will transmit a momentary ringing current impulse out over this trunk to operate the ring-up relay 14 in the cord circuit O. This relay in turn locks up and causes the supervisory lamp 12 to be lighted. The replacement of the receiver at the called station causes a supervisory relay 112 (Fig. 2) to deenergize to in turn cause the relay 120 to deenergize to again connect the line relay 141 in bridge of conductors 81 and 82. Since the reversing relay 128 is still energized, the polarized relay 20 in the cord circuit O will now be operated in the proper direction to cause the disconnect lamp 19 to be lighted. The operator upon noting that both disconnect lamps 12 and 19 are lighted knows that

the conversation has been completed and proceeds to pull down the connection. When the plug is removed from the answering end of the cord, the circuits of relays 2, 5 11 and 14 are broken and these relays are restored to normal. When the plug is removed from the calling end, the circuit for line relay 141 of the selector E is interrupted to bring about the release of the switches 10 D, E and H, in the same manner as described when the called line was busy.

Interception of calls from dead levels in the toll selector.

15 Before proceeding with the description, Fig. 7 of the drawings should be placed at the left of Fig. 1, with the corresponding lines in alignment. Fig. 6 should also be placed at the left of Fig. 7. It may be well 20 to explain at this time that in order to avoid the necessity of showing the individual line switch, such as C² associated with each of the relay groups RG', RG², etc., the drawings have been so arranged that during the 25 process of describing the operation of these various relay groups the drawing showing switch C² may be shifted from one relay group to another.

It will now be assumed that the first digit 30 of the number given the operator is incorrect. It will be assumed further that the first digit of the number given the operator corresponds to a dead level in the bank of the selector D. The operator not knowing this, however, proceeds to set up the connection in the usual manner. The bank contacts 47-49, inclusive, represent the bank contacts of a dead level in the selector D, and it will be assumed that this is the particular level selected by the operator. As 40 soon as the selector D takes its first rotary step, in the same manner as previously described, the test wiper 42 engages the first bank contact 48 of the selected level.

45 In cases where there are very few calls trunked to dead levels, only one relay group, such as the group RG', need be provided, this relay group being multiplied to all sets of contacts in the dead level. If, however, 50 the traffic to these dead levels is such that one relay group is insufficient, the contacts in the dead level may be split up into two or more groups, each group then being provided with relay equipment, such as RG'.

55 Returning now to the operation of the selector D, it will be assumed that the level selected has its contacts divided into more than one group, and that the first group engaged is busy. The test contact 48 will 60 be grounded as well as other test contacts common to the same relay group RG', and the selector D will operate in the manner previously described until a test contact 48 associated with an idle relay group RG' is 65 ground, at which time no ground potential

will be present on the test contact 48 and the selector D will switch through in the manner previously described. The switching relay 54 upon operating extends the trunk conductors 56 and 57 to conductors 16 70 and 18, which latter conductors are provided with branches extending by way of armatures 77 and 79 and their resting contacts to the winding of relay 64 to ground and battery, respectively. Another circuit 75 extends by way of grounded release trunk conductor 24, working contact and armature 40 of relay 54 to the conductor 17, which has connections extending by way of armature 75 and its resting contact, and resting contact and armature 69 and the said armature to the windings of relays 61 and 62, respectively. Relays 64, 61 and 62 operate over the above traced circuits. Relay 64 upon operating, at its armature 76, completes a circuit for slow release relay 66. This latter relay in turn operates and at its armature 84 applies ground to the conductor 17 to maintain the switching relay 54 and relays 61 and 62 operated after the slow 80 relay 28 deenergizes, and at its armature 80 applies ground to the conductor 742. Relay 61 upon operating, at its armature 73, prepares a point in the operating circuit of relay 60, and at its armature 74 closes a 85 point in the locking circuit of relay 62. Relay 62 upon operating, at its armature 70, completes a locking circuit for itself, and at its armatures 72 and 71 disconnects conductors 743 and 741 from upper winding of 90 relay 62 and ground, respectively, and connects these conductors to conductors 16 and 18. The ground applied to conductor 742 by the operation of relay 66 extends by way 95 of conductor 742 through the pull down 105 winding 745 of line switch C², springs 738 and 739, conductor 748, armature 733 and its resting contact to battery. The line switch C² operates and by the operation of 110 its armature 748 causes the holding winding 115 and battery to be switched in series with the pull up winding 745, thereby maintaining the switch C² operated independent of the battery formerly supplied through armature 733. The operation of the line switch C² 120 also causes the bank contact springs 718, 720 and 722 to engage their associated springs 717, 719 and 721. Springs 719 and 720 upon closing complete a circuit extending 125 to the master switch bank contact upon which the master switch wiper 723 is now resting, energizing the starting relay 734 of the master switch MS. Upon energizing, the relay 734 closes a circuit for the locking magnet 732, which unlocks the master switch 130 shaft and thus brings about the re-alignment of all idle line switch plungers before bank springs in which is terminated the next idle trunk line. The starting relay 734 also closes a circuit for the open main relay 135

731, which, upon energizing, disconnects the common conductor 748 from the negative pole of the battery in order to prevent any of the line switches from being operated 5 until the master switch comes to rest. The closure of springs 717 and 718, and 721 and 722 causes the conductors 741 and 743 to be extended to the trunk line conductors 708 and 709 which terminate in the jack J⁵ at an 10 intercepting operator's position in the centrally located office.

The operator, not knowing that she has set the wipers of the selector on a dead level, will continue to operate her calling device 15 in accordance with the remaining digits of the called number. Since the selector D has cut through and extended the conductors 57 and 56 into connection with the conductors 16 and 18, across which is bridged the 20 relay 64, the remaining series of impulses will merely cause this relay to vibrate. Relay 66, however, being of the slow acting type, remains operated during this time. The operator having completed the dialling 25 of the called number, restores the key K' to normal, substituting therefor the polarized relay 20 in the manner previously described. It will be noted that the battery and ground connections of the relay 64 are such that the 30 current flow over conductors 56 and 57 is the same as had the connection been completed to an idle called line and therefore polarized relay 20 operates, causing the lamp 19 to glow to indicate to the operator that 35 the called line is idle and that she may initiate the automatic ringing at any time. This time when the operator causes a ringing current impulse to be transmitted out over conductors 57 and 56, which are now 40 connected to conductors 16 and 18, the alternating current relay 63, which is also in bridge of conductors 16 and 18 in multiple with relay 64, is operated, and at its armature 75 opens the locking circuits of relays 45 61 and 62. These relays, accordingly, de-energize. Due to the slow acting feature of relay 61 the deenergization of this relay is slightly delayed and therefore when armature 75 of relay 64 engages its working contact, a circuit is completed for relay 60. Relay 60 upon operating, at its armature 68, locks itself up over a circuit independent of 50 relays 61 and 63 and at its armature 67 applies interrupted generator to the upper winding of cut-off relay 62. Since the relay 62 is now at normal, ringing current is transmitted to the ring up relay 714 at the intercepting operator's position. This circuit may be traced from interrupted generator working contact of armature 67 and the said armature, upper winding of cut-off relay 62, resting contact of armature 71 and the said armature, conductor 743, bank springs 722 and 721, conductor 709, condenser 724, lower winding of relay 714 ar-

mature 713 and its resting contact, conductor 708, bank springs 717 and 718, conductor 741, and armature 72 and its resting contact to ground. Ring up relay 714 operates over the above traced circuit and completes 70 a locking circuit for itself at armature 716, and at its armature 715 completes a circuit for the call signal lamp 700. The intercepting operator, upon noting the lighted condition of lamp 700, responds by inserting the 75 plug P⁵ of the cord circuit O' into the answering jack J⁵. A circuit is now completed for relay 630. This circuit extends from battery, winding of the said relay, springs controlled by armature 631, resting 80 contact of armature 628 and the said armature, conductor 613, ring terminal of the plug P⁵, ring side of the jack J⁵ and springs controlled by armature 711 to ground. Upon operating, relay 630 at its armature 85 631 disconnects direct ground from the winding of relay 630 and substitutes therefor the sleeve relay 710 and ground. Relay 710 operates and opens the energizing and locking circuits of relay 714. Relay 630 at 90 its armature 629 also completes a circuit for slow relay 624, which operates to in turn complete the circuit of slow relay 626. Before the relay 626 has had time to actuate its armature a ground impulse is transmitted out over conductor 613 by way of ground supplied by the actuated armature 632. This ground impulse is of short duration, but is of sufficient duration to cause the operation of ring cut-off relay 62. Relay 62 95 upon operating, at its armature 70, completes a locking circuit for itself and at its armatures 71 and 72 disconnects conductors 743 and 741 from generator and ground and connects these conductors to conductors 18 100 and 16, respectively. Relay 626 upon operating, at its armature 628 and its working contact, closes a bridge across conductors 612 and 613, which includes the impedance coil 604 and high resistance polarized relay 610 105 in series. Conductors 612 and 613 now extend to conductors 741 and 743 across which are bridged the windings of relay 65. The resistance of relay 610 is very high compared with that of relay 65, and this latter 110 relay therefore does not energize at this time. The polarized relay 610 is poled to swing its armature to the left when the call being intercepted is from a toll switch, battery being applied over the ring conductor, 115 and therefore in this instance operates and completes a circuit for relay 622. Relay 622 upon operating at its armature 621, completes a holding circuit for itself, and at its armature 623 short circuits the winding 120 of polarized relay 610, which accordingly restores its armature to normal. As soon as relay 610 is short circuited, the current flow through relay 65 in the relay group 125 RG' is increased sufficiently to cause this 130

relay to energize. Relay 65 upon operating, at its armature 78, applies ground to relay 66 independent of armature 76, and at its armatures 77 and 79 disconnects the relays 63 and 64 from in bridge of conductors 16 and 18. As a result the polarized relay 20 in the cord circuit O deenergizes, causing the lamp 19 to be extinguished, thereby indicating to the toll operator that the call 10 has been answered. The intercepting and toll operators, after throwing their keys K^2 and K , respectively may now converse. When the intercepting operator has given 15 the toll operator the necessary information regarding the desired called number, she pulls down the connection. The withdrawal of the plug P^5 from the jack J^5 breaks the circuits of relays 630 and 710. The relay 630, upon deenergizing, brings about the restoration of relays 622, 624 and 626. Relay 20, upon deenergizing, again completes the normal connections of relay 714. All apparatus at the intercepting operator's position is now at normal. The withdrawal of the 25 plug P^5 also causes the deenergization of relay 65 of the relay group RG^2 . This relay, upon deenergizing, again connects the relay 64 in bridge of conductors 16 and 18. The connection of relay 64 in the above 30 bridge causes the polarized relay 20 in the cord circuit O to again operate causing the lamp 19 to glow to inform the toll operator that the intercepting operator has disconnected her cord from the trunk. The toll 35 operator, accordingly, withdraws the plug P' from jack J' , thereby opening the operating bridge of relay 64. Relay 64 upon retracting its armature opens the circuit of relay 66, which in turn deenergizes, removing ground from the holding circuit of 40 switching relay 54. Relay 54 upon retracting its armatures completes the previously described circuit for restoring the selector D to normal. The deenergization of relay 45 66 also causes ground to be removed from conductor 742 to permit the line switch C^2 to also restore to normal.

50 *Interception of calls from dead levels in toll transmission selectors.*

It will now be assumed that the second digit of the called number given to the toll operator is incorrect instead of the first digit. It will be further assumed that this 55 second digit corresponds to the dead level comprising bank contacts 179, 180, 181, and 182 of the selector E. When the selector E is operated to position its wipers opposite the desired level, the automatic rotary movement is initiated in the same manner as 60 previously described. Since trunk selecting operations by the selector D as well as of the selector E have been previously explained, it will be assumed that the first re-

lay group RG^2 of the dead group terminating in contacts 179, 180, 181, and 182 is idle. The switching relay 152 therefore energizes, at its armature 155 opening the vertical magnet operating circuit, at its 70 armature 156 connecting ground to wiper 173 to make this trunk line busy to other selectors, and at armature 154 removes ground from the holding circuit of relay 108, which relay now deenergizes. Relay 108, 75 upon deenergizing, at its armature 109 closes a point in a holding circuit for relay 184 and at its armature 110 closes the previously described operating circuit of reversing relay 128. Relay 152 also at its armatures 80 153 and 154 extends the trunk conductors 132 and 133 to the conductors 192 and 195. The ground applied to the test wiper 173, by the operation of the switching relay 152, causes the energization of cut-off relay 184. 85 Relay 184 upon operating, at its armature 186, completes a circuit for relay 185, at its armature 187 closes a point in a locking circuit for itself, and at its armatures 183 and 188 extends conductors 192 and 195 into 90 connection with conductors 741' and 743'. Relay 185 upon operating, at its armature 189, completes a locking circuit for itself independent of relay 184, at its armature 191 completes a locking circuit for relay 95 184, at its armature 190 opens the original energizing circuit of relay 184, and at its armature 192 connects interrupted generator to the upper winding of relay 184. It should be noted that the grounding of conductor 742' by the operation of switching relay 152 also caused the switch C^2 to be 100 operated in the same manner as previously described when the call was intercepted from a first selector level. The remaining 105 series of impulses transmitted by the toll operator will now cause the line relay 141 of the selector E to vibrate as previously described. This operation, however, will be without effect since the operating circuit is 110 opened at armature 155 of the switching relay. The operator having completed her dialling operation now restores key K' to normal, substituting the polarized relay 20 as before. Reversing relay 128 being now 115 energized, the current flow is in the proper direction to operate the polarized relay, causing the lamp 19 to glow to indicate to the toll operator that the called line is idle, and that she may initiate the automatic ringing at any time. The relay 128 being in 120 operated position, alternating current relay 130 is again in bridge of conductors 81 and 83 and therefore responds as before to energize slow relay 114, and relay 114 upon 125 operating, at its armature 116, removes ground from the conductor 151 which now extends by way of wiper 172 to the holding winding of cut-off relay 184 causing this relay to deenergize. Relay 184 upon re-

tracting its armatures 183 and 188 now connects interrupter generator and ground, respectively, to conductors 741' and 743'. This interrupted generator causes ring up relay 714 to operate in the manner previously described. When the intercepting operator answers the call, the ring cut-off relay 184 operates in the same manner as did the ring cut-off relay 62 of relay group RG¹ (Fig. 1). Relay 184 upon operating, at its armature 187, again locks up over the previously described circuit, relay 114 having deenergized by this time, at its armatures 183 and 188 disconnects conductors 741' and 743' from generator and ground, respectively, and connects these conductors to conductors 192 and 195, respectively. Battery and ground is now supplied by supervisory relay 112 and by the back contact of relay 108, (relay group B) causing the polarized relay 610 in the intercepting operator's cord circuit to be operated, relay 112 not being operated due to the high resistance of relay 610. Relay 610 upon operating, causes the operation of relay 622, which latter relay short circuits the polarized relay causing the current flow to be increased sufficiently to permit the operation of supervisory relay 112. Relay 112 upon operating causes the energization of relay 120, which, in the manner previously described, removes battery and ground from conductors 81 and 83, causing the deenergization of the polarized relay 20, resulting in the lamp 19 being extinguished to notify the operator that the called party has responded. Conversation may now take place. As soon as the conversation between the intercepting operator and the toll operator has been terminated, the intercepting operator upon withdrawing the plug of the cord from the associated jack thereby opens the bridge for maintaining supervisory relay 112 of the relay group B operated. This relay accordingly deenergizes, again bridging the line relay 141 across conductors 81 and 83. The polarized relay 20 now operates causing lamp 19 to glow to notify the toll operator that the intercepting operator has withdrawn the plug of her cord from the trunk line. The toll operator upon withdrawing the plug P' from the jack J' causes the selectors D and E to restore in the usual manner. As soon as relay 152 of the selector E deenergizes, ground is removed from wiper 173, causing the holding circuit of relays 184, 185, and line switch C² to be broken, accordingly, these relays, and line switch also restore to normal.

Interception of calls from line terminals in connector banks.

It will now be assumed that all digits of the called number as given the toll operator are correct, but that the desired subscriber's

line is out of order. It will further be assumed that in preference to having this subscriber's line entirely out of service that the attendant in the local office has separated the conductors normally extending to the line terminals of the connector bank from the subscriber's line and has retrunked them by way of the cord O³ to the relay group RG³ and to conductors 433 and 434 terminating in answering equipment at a place readily observed by the attendant. Responsive to the final digit of the called number, the connector is positioned on the terminals of the desired line, and assuming that this line is idle at this time, switches through in the manner previously described. The operator therefor operates her ringing key to transmit an alternating current impulse to initiate the automatic ringing as before. This ringing current flows out over conductor 370 by way of conductor 402 of the cord O³, conductor 431, resting contact of armature 860, condenser 833, and the winding of relay 864 to ground. Relay 864 upon operating, at its armature 865 completes a locking circuit for itself and at its armature 866 applies ground to conductor 742². The grounding of conductor 742² causes the line switch C² to operate and seize an idle trunk in the same manner as previously described. Since nothing has happened to cut off the ringing current supplied by the connector, this ringing current is now transmitted by way of conductor 743², bank contact springs of the line switch C², conductor 709, ring up relay 714 and back over conductors 708, 741, 741², 432, 403, 372 and 363 to ground, causing relay 714 to operate in the manner previously described. The response of the intercepting operator causes ring cut-off relay 335 of the connector H to operate and lock up in the same manner previously described, with reference to cut-off relay 62, at the same time transferring the conductors 362 and 363 from connection with ringing generator and ground into connection with conductors 167 and 170, which now extend back over the previously traced circuit to conductors 104 and 105, across which is bridged the supervisory relay 112. Current supplied by supervisory relay 112 is sufficient to cause the operation of polarized relay 610 of the intercepting operator's cord, and relay 850 in the relay group RG³. Relay 850 upon operating, at its armature 851 completes a circuit for relay 856. This latter relay, upon operating, at its armatures 857 and 860, disconnects relays 861 and 864 from in bridge of conductors 431 and 432, at its armature 858 removes ground from the locking winding of relay 864 causing this relay to deenergize, and at its armature 859 applies ground to conductor 742² in substitution of the ground formerly supplied by relay 864. Relay 610 upon operat-

ing, completes the previously described circuit of relay 622. Relay 622 upon operating, short circuits the winding of relay 610 as before, which permits sufficient current to flow to cause supervisory relay 112 to operate. Relay 112 upon operating, brings about circuit changes, which have previously been described, for causing lamp 19, in the toll operator's cord circuit, to be extinguished to notify her that the called party has responded.

The intercepting operator may now operate her listening key and converse with the toll operator. At the termination of the conversation the intercepting operator terminates the connection in the same manner as previously described. The disconnection of the cord O' causes relay 850 to deenergize. Relay 850, upon deenergizing, opens the circuit of relay 856. This latter relay, upon deenergizing, again connects relays 861 and 864 in bridge of conductors 431 and 432 and removes ground from conductor 742², thereby permitting the line switch C² to restore to normal.

In certain cases the plug P³ is reversed before being inserted in jack J³ for a purpose which will subsequently be made clear. When the plug P³ is inserted as above pointed out, it will be seen that when ringing current is connected to conductor 370 this current will be extended by way of spring 422, spring 429, conductor 403 of the cord O³, conductor 432, resting contact of armature 857 and the said armature, condenser 832 and the lower winding of relay 861 to ground. Relay 861 upon operating, at its armature 863, applies ground to conductor 742² to cause the operation of line switch C², at its armature 862 completes a locking circuit for itself, and at its armature 867 closes a circuit for reversing relay 852. This latter relay upon energizing at its armatures 853 and 855 disconnects conductors 432 and 431 from connection with conductors 741² and 743² and connects conductor 741² to conductor 431, and conductor 743² to conductor 432, thereby straightening out the reversal made by reversing plug P³ in the jack J³. When the intercepting operator responds, relay 850 energizes, as before, completing a circuit for relay 856. This latter relay upon energizing, at its armatures 857 and 860, disconnects relays 861 and 864 from its bridge of conductors 432 and 431, at its armature 859 supplies ground to armature 742² in substitution for the ground formerly supplied by armature 863, and at springs controlled by armature 858 opens the locking circuit of relay 861. This relay, accordingly, deenergizes. Relay 856 at its armature 858 and its working contact also completes a locking circuit for relay 852. It will be evident that the effect of the reversal in cord O³ having been nullified by the op-

eration of reversing relay 852, the supervisory circuits will remain unchanged and will be the same as previously described. The disconnection of the intercepting operator's cord from the associated jack is followed by the deenergization of relays 850, 856 and 852, and the restoration of the line switch C² to normal.

Calls between subscribers in the same exchange.

In order to be better able to describe the operations which take place when local calls are intercepted, it will be advisable to describe the usual operations which take place when a local connection is completed. For this purpose it will be assumed that a subscriber at substation A desires to establish a connection with a subscriber at substation A'.

When the receiver is removed at substation A, a circuit is completed over the line conductors 511 and 512 for the line relay 514 of the individual line switch C. Upon energizing, the line relay completes at its armature 520 a circuit which extends through the switching relay 513 and the stepping magnet 515 in series to battery, and at its armature 519 connects the test wiper 526 to the above circuit at a point midway between the switching relay and the said stepping magnet. The operation now depends upon whether the first selector trunk with which the wipers of the line switch are in connection is busy or is not busy. If this trunk line is busy the test contact 531 associated therewith will have a ground potential upon it, the switching relay 513 will be short circuited, and the stepping magnet 515, which interrupts its own circuit, will operate as a buzzer to advance the wipers 525-527, inclusive, step by step in search of an idle trunk line. This operation will continue as long as the test wiper 526 continues to engage grounded or busy test contacts. However, we may assume that in the present case when the call is initiated the selector F is idle, and the test contact 531 therefore is not grounded. Under these circumstances when the line relay 514 is energized the switching relay 513 is energized immediately afterwards, with the result that the line conductors 511 and 512 are disconnected from the winding of the line relay 514 and from ground, respectively, and are extended by way of armatures 516 and 518 and their working contacts, wipers 525 and 527, bank contacts 530 and 532, and armatures 539 and 540 and their resting contacts, to the upper and lower windings of the line relay 535 of the selector F.

The line relay 535 is energized followed by the energization of the release relay 536. The selector F is now in readiness to be operated in response to the first series of im-

pulses transmitted by the calling subscriber. Since the selector F is identical to the previously described selector D, the description of operation of the selector F will not be necessary. It will be sufficient to assume that the calling subscriber caused the wipers 550-552, inclusive, to be elevated to the level in which bank contacts 553-555, inclusive, are located. It will further be assumed that bank contacts 553-555, inclusive, are the first bank contacts engaged by the wipers of selector F, and that the connector H associated with this particular set of bank contacts is idle when the selector takes its first rotary step. As a result, the switching relay 537 of the selector F therefore energizes, and at its upper and lower armatures disconnects the conductors 533 and 534 from connection with the line relay 535 and connects these conductors with conductors 301 and 303, across which are bridged the windings of line relay 312 of the connector H. It should be noted that this circuit for line relay 312 does not include the upper winding of relay 326, as was the case when the connector H was seized by a toll selector. Line relay 312 upon operating completes a circuit for slow release relay 314, which latter relay also operates and at its armature 315 applies ground to the release trunk conductor 302, this ground being applied for the usual purpose of maintaining the test contact 554 of the selector F busy to other selector switches, and for maintaining the selector F and the line switch C in operated position. Relay 314 also, at armature 317, applies ground to release conductor 169 terminating in bank contact 177 so as to make the connector H busy to toll selectors, such as the selector E, and a armature 316 prepares the usual operating circuits of series relay 318 and vertical magnet 311. The connector H is now in readiness to receive impulses transmitted by the calling subscriber. Since the operation of the connector H as regards the vertical and rotary movement is the same as when operated by way of a toll switch train, the description of this phase of the operation will be omitted. Starting with the description at the termination of the final series of impulses transmitted to connector H, it will be assumed in this case that the subscriber's line is idle. The slow relay 345, upon deenergizing, completes the previously described circuit for switching relay 348. This latter relay upon operating, at its armature 353, completes a locking circuit for itself which extends by way of armature 317 and its working contact and armature 329 and its resting contact. At its armature 352 relay 348 opens the operating circuit of rotary magnet 364, at armature 355 disconnects the test relay, at armature 351 applies direct ground to test wiper 357 to make the associated test contact 367 busy to other connector switches, and at armatures 349 and 354 applies the usual generator and ground to conductors 370 and 372 which extend by way of the usual protective apparatus in the distributing frame 421 to the subscriber's line. When the called subscriber responds, the ringing relay 335 operates in the usual manner, completes a locking circuit for itself at its armature 337, and at its armatures 336 and 338 disconnects ringing generator and ground from conductors 362 and 363 and connects these conductors to conductors 324 and 325, respectively. This places the back bridge relay 306 in bridge of the called subscriber's line. Relay 306 upon operating, at its armature 309, opens a point in the circuit of release magnet 330, at armature 310 applies ground to conductor 169 independent of contacts controlled by release relay 324, and at its armatures 307 and 308 reverses the direction of current flow as regards the calling subscriber's line to effect the operation of meters or coin collect devices in cases where the calling subscriber's line is equipped with such apparatus. Conversation may now proceed in the usual manner.

At the termination of the conversation, the calling and called subscribers replace their receivers. The replacement of the receiver at the calling station causes line and release relays 312 and 314 to deenergize. Relay 314 upon deenergizing at its armature 315 removes ground from release trunk conductor 302, permitting the line switch C and the selector F to restore to normal in the usual manner. Relay 314 at its armature 316 prepares a point in the operating circuit of release magnet 330. When the called subscriber replaces his receiver, back bridge relay 306 deenergizes, at its armature 310 removes ground from the test contact 177, and at its armature 309 completes a circuit for release magnet 330. Release magnet 330, upon operating, causes connector H to be restored to normal in the usual manner. The above is the sequence of operations which takes place if the calling subscriber is the first one to replace his receiver. If the called subscriber replaces his receiver first, however, back bridge relay 306, upon deenergizing, will merely prepare the circuit for release magnet 330. When the calling subscriber replaces his receiver the release of line switch C and the selector F is the same as previously explained, but in this instance the deenergization of relay 314 also completes the circuit of release magnet 330 of the connector.

Interception of calls from dead bank levels in local selectors.

It will now be assumed that the calling subscriber has been misinformed as regards the first digit of the called subscriber's num-

ber. It will further be assumed that the first digit dialled by the calling subscriber corresponds to a dead level of the selector F, in which bank contacts 556-558, inclusive, are located. As soon as test wiper 551 engages the bank contact 557 having associated with it an idle relay group RG⁴, the selector F switches through in the usual manner, connecting the conductors 534 and 533 with conductors 559 and 560, across which are bridged the windings of relay 564 of the relay group RG⁴. Relay 564 upon operating, at its armature 565, completes a circuit for relay 561. This latter relay upon operating, at its armature 562, applies ground to bank contact 557 in order to make this relay group busy to other selector and to prevent the release of line switch C and selector F when slow relay 536 deenergizes a moment later, and at its armature 563 applies interrupted generator to the upper winding of ring cut-off relay 572. Relay 561, at its armature 562, also causes ground to be extended by conductor 742⁴ to the line switch C², causing this line switch to operate in the manner previously described. Ringing current now flows by way of conductor 743⁴ and over the previously described circuit to operate the ring up relay 714 at the intercepting operator's position.

The subscriber at substation A not knowing that the call has been trunked to an intercepting operator's position continues to dial as did the toll operator, but without effect other than to cause the relay 564 to vibrate its armature.

The intercepting operator upon responding causes the ring cut-off relay 572 to operate. Relay 572 at its armature 574 completes a locking circuit for itself, and at its armatures 573 and 575 disconnects ringing generator and ground from conductors 743⁴ and 741⁴, respectively, and connects these conductors to conductors 560 and 559. The back bridge relay 566 in the relay group RG⁴ is now in bridge of the previously described polarized relay in the intercepting operator's cord circuit. The current flow in this circuit is not of the proper direction to cause polarized relay 610 in the cord circuit O' to operate. Relay 566 will not operate when the resistance of relay 610 is included in this circuit, and therefore the current flow in the calling subscriber's line will not be reversed, nor is any reversal desired at this time, as the calling subscriber is not required to pay for calls of this character.

The intercepting operator may now operate her listening key and converse with the calling subscriber, informing such subscriber why she has not succeeded in completing the desired connection. The intercepting operator now withdraws the plug of her cord circuit, causing the various relays at her position to be restored to normal

in the manner previously described. The restoration of the receiver at the calling station causes relays 564 and 561 of the relay group to deenergize. Relay 561 upon restoring its armature 562 removes ground from the holding circuit of line switches C², C, and of the selector F, causing these switches to restore to normal in the usual manner.

Interception of local calls extended to line terminals of connector switches.

It will now be assumed that the calling subscriber dialled the proper digit to set up a connection to the substation A', but that the connector bank terminals having conductors normally extending to station A' have now been switched to the relay group RG³. Following the positioning of the connector wipers upon the terminals of the desired line, the connector switches through and connects ringing current and ground, respectively, to conductors 362 and 363 in the same manner as if the called line were being signalled. Since conductors 370 and 372 are now trunked by way of the cord O³ to conductors 431 and 432, relay 864 in the relay group RG³ will respond in the same manner as when this relay group was seized by the connector H in a toll connection. The operation of the line switch C² and the call signal equipment of the trunk line Y will also be the same.

When the intercepting operator responds, causing the energization of the cut-off relay 335, in the manner previously described, conductors 324 and 326, across which are bridged the windings of back bridge relay 306, are now extended by way of springs controlled by armatures 331 and 334, working contacts of armatures 336 and 338 and the said armatures to conductors 362 and 363, respectively. These latter conductors now extend over the previously traced circuit conductors 612 and 613 of the cord circuit O' across which is bridged the polarized relay 610. The current flow supplied by back bridge relay 306 is in the opposite direction to that formerly supplied by supervisory relay 112 and therefore does not cause the operation of polarized relay 610. Relay 622 is therefore not operated, and since the high resistance of relay 610 is not shunted out, the back bridge relay 306 will not be operated. The operator upon throwing her listening key K² may now converse with the calling subscriber to inform such subscriber that the desired connection cannot be completed. Since reversing relay 306 was not operated the current flow in the calling line conductors remains unchanged, so that if the calling subscriber's line or station is provided with paystation or metering apparatus such apparatus is not operated to charge for the call. The release of line switch C and the selector F in this

case is brought about in the same manner as if the connection had been completed to the desired called line. Likewise, the release of the connector H is brought about in 5 the same manner when the intercepting operator disconnects her cord as when a called subscriber replaces his receiver.

Interception of calls initiated by subscribers whose lines are temporarily out of order.

In order to describe the next phase of the invention, Figs. 4, 8 and 9 should be laid out and arranged as shown in Fig. 11. It sometimes happens that a subscriber's line is 15 temporarily out of order due to swinging grounds or similar causes. When conditions of this kind exist it is desired, if at all possible, that the subscriber affected be given some kind of service so that such subscriber 20 may get a connection completed for him in an emergency case. In order to do this the affected line is trunked by means of the cord O³ to the call signal equipment in the associated office. This call 25 signalling equipment is such that when a subscriber wishes to initiate a call, upon operating either the dial or the receiver hook, causes a lamp to flash. The attendant upon noting the flashing of the lamp responds by 30 inserting the plug of a cord in the jack of the calling line and throws a listening key. Upon conversing with the calling subscriber and ascertaining that such subscriber wishes to have an emergency call completed, 35 the attendant will trunk the call by means of the cord used to an operator's position in some manual office or to a special A operator's position of the system. This operator may then complete the connection in 40 the same manner as if the call had been initiated by a manual subscriber of that office.

In detail the operations which take place when the above type connection is completed will now be explained. For this purpose it will be assumed that a subscriber at 45 substation A' wishes to complete a call, and it will be further assumed that line conductor 435 is temporarily grounded. When the calling subscriber removes his receiver, 50 ground on conductor 435 is connected by way of the substation apparatus to conductor 436 causing relay 838 to operate. Relay 838 upon operating causes call signal lamp 840 to glow. The calling subscriber, 55 either by operating his switchhook or his calling device, may cause the lamp 840 to flash to further attract the attention of the attendant. The attendant, upon observing the lighted condition of lamp 840 responds 60 by inserting the plug P⁶ in the answering jack J⁶. A circuit is now completed from battery, lamp 841, resting contact of armature 831 and the said armature, sleeve terminals of the plug and jack P⁶ and J⁶, respectively, and the winding of sleeve relay 65 835 to ground. Relay 835 upon operating, at its armatures 836 and 837, disconnects ground and the winding of relay 838 from in bridge of conductors 433 and 434. This latter relay accordingly deenergizes. The 70 relay 830 is operated over the calling subscriber's loop in the usual manner to cut in the resistance 842 in series with lamp 84 and relay 835, thereby preventing the lamp 841 from glowing at this time. The attendant 75 may now operate the key K³ and converse with the calling subscriber. The attendant, upon being informed that it is important that the call be completed, may now insert the calling plug P⁷ into the jack J⁷ of a 80 trunk line extending to an operator's position of some nearby manual office, and momentarily operate the ringing key K⁴. This ringing current is transmitted by way of trunk conductors 800 and 801 to the ring 85 up relay 901 in the manual office. Relay 901 upon operating, at its armature 905, completes a locking circuit for itself, and at its armature 904 completes a circuit for call signal lamp 900. This lamp upon glowing 90 informs the operator in the manual office that a call is awaiting her attention. The operator responds by inserting the answering plug P⁹ into the jack J⁹. A circuit 95 is now completed for supervisory relays 906 and 824. This circuit extends from battery, the lower right hand winding of repeating coil R, supervisory relay 906, ring terminal of plug P⁶, ring side of jack J⁹, conductor 100 801, ring side of jack J⁷, ring terminal of plug P⁷, springs of key K⁴, lower left hand winding of repeating coil R', winding of the relay 824, upper left hand winding of repeating coil R', through springs of key K⁴, tip of plug P⁷, tip side of jack J⁷, conductor 800, tip side of jack J⁹, tip of plug P⁹, and the upper right hand winding of repeating coil R to ground. Relay 824, upon operating, causes supervisory lamp 817 to 105 be extinguished, thereby notifying the attendant that the operator in the manual office has responded. Relay 906, upon operating, short circuits supervisory lamp 910 so that this lamp does not glow at this time. The operator in the manual office may now 110 operate listening key K⁵ and converse with the calling subscriber, and upon ascertaining the desired subscriber wanted, proceeds to complete the connection. The operator upon ascertaining that the 115 desired subscriber is located in the same office as is the substation A' inserts the calling plug P¹⁰ in the jack J¹⁰ associated with a trunk line extending to and terminating in a line switch C³ in that office. A circuit is now completed from the 120 grounded sleeve of jack J¹⁰, sleeve terminal of the plug P¹⁰, through the supervisory lamp 915 to battery causing this lamp to glow. When plug P¹⁰ is inserted in jack 125 130

J¹⁰ polarized relay 913 is also bridged across conductors 911 and 912, but normal exchange battery flows in the wrong direction to operate it. The operator now proceeds by operating calling device key K⁶, thereby bridging the calling device S in bridge of conductors 911 and 912 in substitution of polarized relay 913. Line switch C³ operates in exactly the same manner as did the line switch C when the subscriber at substation A initiated a call, and has access to the same group of first selectors. It is assumed in the present case that the line switch C³ seizes the selector F. The operator may now operate the calling device S' in accordance with the various digits of the called number, causing the selector F, and connector, such as the connector H, to be operated to complete the connection in the usual manner. Assuming the called subscriber's line to be idle, ringing current will be automatically initiated and when the called subscriber responds this ringing current will be cut off and the back bridge relay of the connector will operate to reverse the direction of current flow in conductors 911 and 912. The operator prior to this time having restored the calling device key K⁶, the polarized relay 913 is again in bridge of conductors 911 and 912, and now operates to complete a circuit for supervisory relay 911. Relay 911 upon operating shunts out supervisory lamp 915 to notify the operator that the called subscriber has responded. Conversation may now take place between the calling and called subscribers.

When the conversation has been completed, the restoration of the receiver at substation A' causes the deenergization of supervisory relay 830. Relay 830 upon restoring its armature 831 shunts out the resistance 842, permitting supervisory lamp 841 to glow to indicate to the attendant that the calling subscriber has replaced his receiver. The called subscriber upon replacing his receiver causes the back bridge relay of the connector switch used to deenergize, thereby again reversing the current flow in the conductors 911 and 912 causing polarized relay 913 to deenergize and open the circuit of supervisory relay 911. This latter relay upon retracting its armature again permits supervisory lamp 915 to glow, thereby indicating to the operator in the manual office that the called subscriber has replaced his receiver. The operator in the manual office upon withdrawing the plug P¹⁰ from the associated jack causes the release of the switches used in the same manner as if they had been released by a local calling subscriber. Upon withdrawing plug P⁹ from the associated jack, the supervisory relay 824 in the cord circuit O⁴ will deenergize causing supervisory lamp 817 to glow to inform the attendant that the operator

in the manual office has broken the connection. The attendant upon noting the lighted condition of supervisory lamps 817 and 814 knows that the conversation has been terminated and accordingly pulls down the connection. The attendant needn't wait for both disconnect signals, but if he desires may disconnect his cord when either signal is displayed.

If it should happen that line conductor 436 is grounded the attendant simply reverses plug P³ of the cord O³ and calls will be handled the same as described above.

When a repairman goes out on a line to find the trouble, the cord O² is plugged in so that ground comes in on conductor 439 causing relay 838 to remain operated. The attendant operates key K⁸ thereby preventing lamp 840 from glowing until the ground has been removed from the line. By this means the attendant may inform the repairman when the line has been cleared.

Interception of calls initiated by an operator in a manual office.

It will now be assumed that the first digit given the operator in the manual office by the attendant or by the subscriber at substation A' is incorrect. It will further be assumed that the operator transmitted the required number of impulses to position the wipers of selector F opposite the dead level bank contacts 556-558, inclusive, and that the selector F rotated its wipers into engagement with these contacts, causing the relays in relay group RG⁴ and the line switch C² to operate in the manner previously described. The operator, not knowing that the call has been intercepted at a selector level, will complete the dialling of the desired number before restoring key K⁶. When the intercepting operator responds, the current flow supplied to polarized relay 610 by relay 566 being in the wrong direction, polarized relay 610 does not operate, and, of course, due to the high resistance of relay 610 relay 566 cannot operate. As the current flow supplied to the polarized relay 913 by relay 564 remains unchanged, the supervisory lamp 915 will continue to glow indicating to the operator in the manual office that the called subscriber has not responded. The intercepting operator upon throwing her listening key, may converse with the calling subscriber, and upon ascertaining that the call has been set up by way of an operator, operates flash key K⁹. Each time this key is operated, the winding of polarized relay 610 is short circuited and the current flow through relay 566 is increased sufficiently to permit this latter relay to operate. Relay 566 upon operating reverses the direction of current flow supplied to polarized relay 913, causing this relay to operate to complete a circuit for su-

pervisory relay 911. Relay 911 upon operating shunts out lamp 915. By this means the intercepting operator can call the operator in the manual office to inform her that 5 she has dialled an incorrect number. The intercepting operator upon disconnecting her cord from the connection causes relays at her position to be restored to normal in the manner previously described. The normal current flow through relay 913 being restored, relay 913 deenergizes and opens the circuit of relay 911 causing lamp 915 to glow, thereby indicating to the operator in the manual office that the intercepting operator has disconnected her cord from the connection. The operator in the manual office need not, however, wait for this disconnect signal, but may withdraw the plug P¹⁰ causing the release of the line switch 20 C³, the selector F and relays 561, 564 and 572 of the relay group RG⁴ in the manner previously described, and, assuming that the operator in the manual office has been given the correct number of the desired subscriber's line, may re-insert the plug P¹⁰ in jack J¹⁰, or some other jack, and proceed to set up the connection.

It will be quite evident that if the call set up by the operator is correctly dialled, and 30 the connector positioned on contacts of the desired called line which is temporarily out of order, that the call will be trunked to the intercepting operator in the same manner as described when the subscriber at substation A set up a similar connection. It will be recalled that in that case the back bridge relay 306 of the connector failed to operate. The relay 306 has relatively the same position in the connection when the 40 call is set up by an operator as the relay 556 of relay group RG⁴ and may be controlled at the option of the intercepting operator in the same way to attract the attention of the operator in the manual office.

45 What is claimed is:

1. In a telephone system, a centralized office, a plurality of branch offices, subscribers' lines, means including automatic switches for completing connections between said lines, contacts in said switches not used for extending connections between said lines, and means comprising an automatic hunting switch associated with said contacts for trunking calls extended thereto to an operator's position in said centralized office.

2. In a telephone system, a centralized office, a plurality of branch offices, subscribers' lines in one of said branch offices, means including a selector and a connector for establishing connections between said lines, bank contacts in said selector not used for completing connections between said lines, an intercepting operator's switchboard at said centralized office, and means

including relay equipment associated with said bank contacts at the branch office for trunking calls extended thereto to said switchboard.

3. In a telephone system, a centralized office, a plurality of branch offices, subscribers' lines, means including selector and connector switches for completing connections between said lines, said connections being established via bank contacts in said switches, bank contacts in each of said switches not in use, means for extending connections to said unused bank contacts, means associated with said unused bank contacts for trunking calls extended thereto to an operator's switchboard in said centralized office, and operator's signal, and means responsive to the trunking of a call to said switchboard for operating said signal.

4. In a telephone system, a centralized exchange, a plurality of branch exchanges, subscribers' lines, an automatic switch provided with groups of bank contacts, means including bank contacts of certain of said groups for extending connections to called lines, conductors extending from other groups of said bank contacts and terminating in line switches, trunk lines extending from bank contacts in said line switches to an operator's switchboard in said centralized office, and means including said line switches for trunking connections extended to said last contact groups to the centralized office via said trunk lines.

5. In a telephone system, a centralized exchange, a plurality of branch exchanges, trunk lines extending from operators' switchboards in the centralized exchange to each branch exchange, subscribers' lines in said exchanges, automatic switches provided with groups of bank contacts, means including said automatic switches and certain of their bank contacts for completing connections between said lines, line switches having access to said trunk lines, conductors extending from other of said bank contacts to said line switches, and means associated with said conductors for causing said switches to trunk calls extended to said contacts to the centralized exchange.

6. In a telephone system, a plurality of exchanges, one of said exchanges being provided with intercepting operators' switchboards, subscribers' lines, automatic switches and certain bank contacts thereof used by subscribers in completing connections between said lines, other automatic switches, other bank contacts in said first switches connected with said other switches, and means including said other switches for automatically trunking calls extended to said other bank contacts to said intercepting operators' switchboards.

7. In a telephone system, a calling subscriber's line normally having direct ac-

- cess via automatic switches to other subscribers' lines, said line also normally directly callable via automatic switches, means for redirecting the calls extended by subscribers on said line via an operator's switchboard, and for also switching calls normally extended to said line to a second switchboard.
8. In a telephone system, a subscriber's line, means including automatic switches normally controllable by subscribers on said line to complete connections to called lines, means for removing the control of said automatic switches from a subscriber's line in trouble, said means also effective to direct calls attempted over said line to an operator's switchboard, means at said switchboard for extending such calls to a second operator's switchboard, and means at said second switchboard for completing the desired connection via certain of said automatic switches.
9. In a telephone system, a plurality of exchanges, an intercepting operator's switchboard common to said exchanges, calling and called subscribers' lines, means including automatic switches for completing connections between said lines, and means for disconnecting any called line from the final switch normally used in completing a connection and for substituting for said line facilities for automatically trunking calls to said intercepting operator's switchboard.
10. In a telephone system, a centralized exchange, a plurality of branch exchanges, calling and called lines associated with each of said exchanges, means including automatic switches controlled by subscribers for interconnecting said lines, and means for disassociating lines from the final switches used to complete connections thereto and for substituting facilities for automatically trunking calls via said final switches to an operator's switchboard in said centralized exchange regardless of the exchange in which the call is attempted.
11. In a telephone system, automatic switches having sets of bank contacts for use in setting up connections between lines,

other unused sets of contacts in said switches, and trunk lines common to said unused sets of contacts for extending calls therefrom to an operator's switchboard.

12. In a telephone system, selector and connector switches for connecting a calling and a called line, trunk contacts in the selectors and line contacts in connectors over which the connections are established, selector and connector contacts unassigned to trunks or lines, a group of intercepting trunks, and means responsive to a call arriving at any unassigned contact for automatically connecting such contact to any idle one of said intercepting trunks.

13. In a telephone system, automatic switches for connecting a calling and a called line, contacts in said switches over which the connections are established, contacts in said switches unassigned, a group of intercepting trunks, and means responsive to a call arriving at any unassigned contact for automatically connecting such contact to any idle one of said intercepting trunks.

14. In a telephone system, automatic switches of different classes having sets of bank contacts for use in setting up connections between lines, other unused sets of contacts in said switches, and trunk lines common to all said unused sets of contacts for extending calls therefrom to an operator's switchboard.

15. In a telephone system, automatic switches having sets of bank contacts for use in setting up connections between lines, said automatic switches including switches for completing subscriber-to-subscriber connections and switches for completing toll connections, other unused sets of contacts in said switches, and trunk lines common to all said unused sets of contacts for extending calls therefrom to an operator's switchboard.

In witness whereof, I hereunto subscribe my name this 4th day of September, A. D., 1923.

JOHN WICKS.
